APPARATUS FOR SUBDIVIDING A MASS

Robert R. Pollard, East Orange, N. J., assignor to
Western Electric Company, Incorporated, New
York, N. Y., a corporation of New York

Application December 29, 1944, Serial No. 570,334

3 Claims. (Cl. 25—105)

This invention relates to material handling apparatus, and more particularly to apparatus for subdividing masses of highly viscous, pseudo-solid liquids such as asphalt, bitumen, coal tar and the like.

Asphalt, bitumen, coal tar and the like substances have many applications as raw material in various arts. As commercially supplied, these substances ordinarily appear in the market in barrels or drums into which they have been poured in a molten state and allowed to solidify as a sensibly solid mass, which, however, is actually, at ordinary temperatures, an extremely viscous and tough liquid, which is also a highly effective heat insulator. It is a problem of considerable difficulty to find suitable means to subdivide such a mass for subsequent treatment. It is too tough at ordinary temperatures to be broken by a hammer or cut by a chisel with any reasonable facility, and will clog any kind of saw almost immediately. Because of its low conductivity of heat, chilling the mass to brittleness or heating it as a whole to fluidity is impractically time consuming, even when the barrel or drum has been split and removed from the generally cylindrical body to be dealt with.

An object of the present invention is to provide simple, reliable, sturdy and effective apparatus for subdividing a pseudo-solid mass of toughly and highly viscous material, e. g. asphalt or the like, into sections or portions amenable to further treatment such as further subdivision, liquefaction by heat, or the like.

With the above and other objects in view, the invention may be embodied in an apparatus for subdividing a mass of highly viscous, pseudo-solid liquid, which apparatus comprises means to support a mass to be subdivided against displacement during subdivision, a plurality of strands to be positioned in loops about the mass, means to releasably lock the strands at one end of each in immovably fixed position when so looped, and means to advance the other ends of the strands to tighten and diminish the loops thereof about the mass and thereby cause the strands to divide the mass into a plurality of sections.

Other objects and features of the invention will appear from the following detailed description of one embodiment thereof, taken in connection with the accompanying drawings in which the same reference numerals are applied to identical parts in the several figures, and in which

Fig. 1 is a view in side elevation with parts broken away of an apparatus embodying the invention;

Fig. 2 is a plan view thereof;

Fig. 3 is a view on the line 3—3 of Fig. 1;

Fig. 4 is an enlarged detail view in horizontal section of the drum lock;

Fig. 5 is an enlarged detail view on the line 5—5 of Fig. 2;

Fig. 6 is an enlarged partial view on the line 6—6 of Fig. 5; and

Fig. 7 is an enlarged detail view of the cutting wire securing means of the drum.

The purpose of the particular apparatus herein disclosed is to subdivide into manageable transverse slices, the cylindrical mass of asphalt or the like obtained by splitting and stripping a metal drum from a content of asphalt formed therein by filling the drum with molten asphalt and allowing the molten charge to cool.

A multiple-slotted, horizontal, stationary platform, generally indicated at 10 is composed of a plurality of parallel, spaced channel beams 11, the intervals between which provide a plurality of parallel slots 12. The outer, right ends of the beams 11 are formed as shown at 14, making a ramp up which a cylindrical mass 15 of asphalt to be subdivided may be rolled to the position on the platform shown. The left hand ends of the beam 11 support a transverse channel 16, to which they are welded. A little to the right of the channel 16, an angle bar 17 as long as a channel 11 is wide, rests on and is welded to each of the channels 11, parallel to the channel 16. A vertical channel 18 is footed on and welded to each channel 11 against the rear face of the upright flange of the angle 17, to which the several posts 18 thus formed are also welded. The channels 18 are of the same width as the channels 11 so that the slots 12 continue up between the posts 18 as shown at 112. Each post 18 is braced by a diagonal angle bar 19 welded to the post and to the far side of the channel 16. The plurality of posts 18 serves as a multiple-slotted stop for the cylinder 15 during the dividing operation hereinafter described. The tops of these posts 18 also serve, during operation of the apparatus, 45 to support a transverse rod 20 whose ends are secured to the ends of a pair of arms 21 pivoted at 22 to the outer faces of the right hand ends of the outer channels 11.

The forward end of the channel 16 extends well 50 forward of the frontmost channel 11, abuts against and is welded to a channel 24 extending leftwardly therefrom. Similarly, the rear end of the channel 16 abuts against and is welded to a leftwardly extending channel 25. A vertical 55 channel 26 is welded to the outer face of the chan-

nel 24, and a similar vertical channel 27 is welded to the outer face of the channel 25. The two vertical posts thus formed by the channels 26 and 27 are tied together at their tops and braced by a transverse channel 28 welded at its end to the posts. A series of angle members 29 is welded to the top face of the channel 28, one member 29 over each channel 11. Each member 29 is also welded at the right end to the top part of the corresponding post 18. A shaft 30 disposed above and parallel to the channel 28 is rotatably supported in the upturned flanges 31 of the angles 29. Centrally over each channel 11, a latch hook 32 is secured on the shaft 30 to turn therewith and is formed at its outer end to hook down over the rod 20 or to be lifted therefrom, as indicated in solid and in broken lines respectively in Fig. 1. Lifting any one of the latch hooks 32, lifts them all since all are pinned or otherwise rigidly secured to the shaft 30. Details of a hook 32 and its mounting are shown in Fig. 5. There is mounted on the rod 20, directly over each slot 12, a device best shown in Figs. 5 and 6 for securing the end of a wire 33 to the rod, there being as many wires 33 as there are slots 12. The device in question is a collar 34 having a radial integral stud 35 in which are formed a diagonal bore 36 and a transverse bore 37, also a radial threaded bore 38 intersecting the transverse bore 35, the diagonal bore 38 being offset from both bores 35 and 37. The end of the wire 33 passes through the diagonal bore and turns back as shown and enters into the transverse bore 35 where it is locked by a jam screw 39 in the threaded bore 38.

A drum 40 is mounted rigidly on a shaft 41 journalled in bearings 42 supported on the channels 24 and 25 respectively, the drum and its shaft being parallel to the shaft 30 and the rod 20. The other ends of the several wires 33 are secured to the drum at points along a geometrical line element of the cylindrical surface thereof, respectively opposite the center lines of the several slots 12. The manner of securing the wires 33 to the drum 40 is so simple and so clearly shown in Fig. 7 as to need no detailed description in words. The wires 33 are alike in length and of such length, preferably, that when the wire carrying frame 21, 20, 21 is turned clockwise on the pivots 22 from its full line position in Fig. 1 to lie out horizontally to the right as indicated in broken lines in the same figure, there will be a turn or several turns of each wire still around the drum.

A sprocket gear 43 is freely rotatable on the shaft 41 and is drivable by a chain 44 driven by a sprocket 45 on the output shaft of a speed reducing gear device 46 whose input shaft is drivable by a motor 47. A lever arm 48 is rigidly secured on the shaft 43 adjacent the sprocket 43 and can be connected to the sprocket to be driven by the sprocket and thereby drive the shaft 41 and drum 40 or can be disconnected therefrom by manipulation of the bayonet lock pin 49 (Fig. 4).

A pair of brackets 53 (Fig. 3) are mounted on the inner faces respectively of the posts 26 and 27, to support respectively two limit switches 52, whose operating levers 51 support and are tied together by a transverse rod 50 parallel to the axis of the drum 40.

The wires 33 are preferably "piano" wire, i. e. steel wire, hard drawn to extremely high tensile strength, but may be strands of any suitable material. They are correspondingly elastic, and when wound tightly on the drum 40 do not take a set and tend to remain coiled, but as soon as

the tension on them is released, will tend to spring loose from the drum as far as any slack will permit. To control this tendency within safe limits, a wooden board 54 is secured on brackets 55 carried on the channel 28 to stand with the width of the board radial to the drum 40 and the outer edge of the board wiping lightly against the cylindrical surface of the drum, this edge being formed with shallow notches 56 to give slight clearance to coils of the wires 33 on the drum.

For operation, assuming that the sections of a sliced mass have just been removed, the apparatus will be in the general state shown in Fig. 1, without the cylinder 15 and with the wires 33 hanging from the bar 20 in a short loop to the drum 40 as indicated in Fig. 1 in broken lines. To prepare to receive another cylinder 15 to be sliced, the pin 49 is retracted from the sprocket 43, leaving the sprocket 43, shaft 41 and drum 40 freely revoluble. The latch hooks 32 are then lifted from the full line position of Fig. 1 to the broken line position, thus releasing the rod 20. The wire frame 21, 20, 21 is then swung (clockwise in Fig. 1) from the full line position of Fig. 1 to lie out flat on the ground to the right, as indicated in broken lines in Fig. 1, the drum rotating freely to allow the wires 33 to be drawn out as required by this action and to move down the slots 112 between the posts 18 and lie out over the slots 12. A fresh cylinder 15 to be cut is then rolled over the bar 20 and wires 33 on the ground and up the ramps 14 onto the channels 11 into the position shown in Figs. 1 and 2. Then the wire frame 21, 20, 21 is swung back into the solid line position of Fig. 1, thus wrapping the wires 33 around the cylinder as shown. The rod 20 is locked in place by bringing down the latches 32; and the pin 49 is again engaged with the sprocket 43. Power is then supplied to the motor 47 thus driving the drum 40 to begin winding the wires 33 thereon and thus to progressively tighten the loops of the wires about the cylinder. The pull of the wires on the cylinder 15 is resisted by the posts 18.

Asphalt, bitumen, coal tar and the like substances are true liquids and quasi solids. They will flow under a continuously exerted force up to a certain degree of pressure per square inch, depending both on the particular substance in question and upon the temperature as well as upon the abruptness with which the pressure is applied. Beyond that pressure they tend to crack and splinter with amygdaloidal fractures like an amorphous solid.

At the proper speed of the drum 40, to be experimentally determined to accord with the material to be cut, its temperature, and the diameter of the slicing wires 33, the material will flow under the wires, part around them and fail to rejoin over them; and thus the wire loops will gradually divide the cylinder 15 into transverse slices completely severed from each other when the last arc of each wire has passed the right hand face of the posts 18.

A moment or two later, one or more of the loops tightens against the rod 50 actuating the limit switches 52. It is to be understood that these switches are connected into the control circuit of the motor 47, so that the motor is stopped when the rod 50 is pressed to the left by the wires 33.

The sliced sections of the cylinder 15 being removed from the platform 10, the above described cycle of operation may be repeated.

The apparatus described above in specific detail is intended as an illustrative embodiment of

the invention and may be variously modified, altered or rearranged without departing from the spirit and scope of the invention as pointed out and delimited in the appended claims.

What is claimed is:

1. An apparatus for subdividing a mass of highly viscous, pseudo-solid liquid which apparatus comprises a platform and vertical posts thereon to support a mass to be subdivided against displacement during subdivision, a plurality of strands to be positioned in parallel loops about the mass, a bar having one end of the strands secured thereto at spaced intervals thereon, an anchorage member rigidly mounted on the platform, means on the anchorage member to releasably lock the bar thereto when the strands are looped about a mass, a winding drum having the other ends of the strands secured thereto at spaced intervals thereon, and motor means to rotate the drum to wind the strands thereon to tighten and diminish the loops thereof about the mass and thereby cause the strands to divide the mass into a plurality of sections.

2. An apparatus for subdividing a mass of highly viscous, pseudo-solid liquid which apparatus comprises means to support a mass to be subdivided against displacement during subdivision, a plurality of strands to be positioned in loops about the mass, a member having one end of each of the strands secured thereto at spaced intervals thereon, means to releasably lock the member in immovably fixed position when the strands are looped about a mass, a winding mem-

ber having the other ends of the strands secured thereto at spaced intervals thereon, means to rotate the winding member to wind the strands thereon to tighten and diminish the loops thereof about the mass and thereby cause the strands to divide the mass into a plurality of sections in combination with a movable member positioned to be moved by a strand which has passed through a mass, and means actuatable by the movable member to stop the winding member rotating means.

3. An apparatus for subdividing a mass of highly viscous, pseudo-solid liquid which apparatus comprises a platform and vertical posts thereon to support a mass to be subdivided against displacement during subdivision, a plurality of strands to be positioned in parallel loops about the mass, a bar having one end of the strands secured thereto at spaced intervals thereon, an anchorage member rigidly mounted on the platform, means on the anchorage member to releasably lock the bar thereto when the strands are looped about a mass, a winding drum having the other ends of the strands secured thereto at spaced intervals thereon, motor means to rotate the drum to wind the strands thereon to tighten and diminish the loops thereof about the mass and thereby cause the strands to divide the mass into a plurality of sections in combination with a rod disposed transversely to the several strands and movable by a strand which has passed through a mass, and means actuatable by the rod when moved by a strand to stop the motor means.

ROBERT R. POLLARD.
